UNITED STATES PATENT OFFICE.

JOHN PETER WULFF, OF CHICAGO, ILLINOIS.

SAFETY VALVE FOR WATER GAUGES.

Application filed November 25, 1921. Serial No. 517,756.

To all whom it may concern:

Be it known that I, JOHN P. WULFF, a citizen of the United States, residing at Chicago, in the county of Cook and State of Illinois, have invented new and useful Improvements in Safety Valves for Water Gauges, of which the following is a specification.

This invention relates to gauges employed in connection with steam boilers for indicating the water level and consisting of a glass tube, one end of which communicates with the water space of the boiler and the other end with the steam space.

An important object of the invention is to provide the gauge with a novel and improved safety valve which prevents the escape of steam and hot water in the event of breakage of the glass tube.

A further object of the invention is to provide a means whereby the valve is automatically opened when the glass tube has been replaced.

Other objects and advantages of the invention will become apparent during the course of the detailed description appearing hereinafter and in order that the same may be better understood, reference is had to the accompanying drawing wherein like reference numerals designate like parts throughout the several views.

In the drawing:

Figure 1 is a sectional elevation showing the invention applied to a boiler;

Fig. 2 is an elevation of the valve showing the method of seating itself in its valve seat, and

Fig. 3 is an end view showing the winged construction of the valve.

Referring specifically to the drawing, numerals 5 and 6 denote upper and lower boiler valve housings, respectively, which are threaded at their inner ends to a boiler 7. Each said housings 5 and 6 carries a valve of the usual type. The parts except as hereinafter noted, are of standard design and hence a detailed description thereof is not necessary.

The lower boiler valve housing 6 has a lateral tubular extension 8 which is upwardly disposed, and the same is provided with a support 9 on which a valve 10 is supported when at rest. This valve 10 has outwardly directed guide wings 11, which terminate at their lower ends below the bottom face 12 of the valve and at their up-

per ends a substantial distance below the top surface 13 of the valve, as clearly shown in Fig. 2. By this construction it will be seen that the wings 11, in addition to their guiding function also serve to elevate the valve from its support to permit the normal passage of liquid therebetween. The top surface 13 of the valve 10 is reduced and has a small leak port 14 therein, as more clearly shown in Figures 2 and 3, the purpose of which will be presently described.

On the free end of the tubular extension 8 is threaded a sleeve or casing 15, the interior wall of which is of the same diameter as that of the tubular extension 8, thus forming a guide for the valve wings 11 when the valve is moved from its normal position on the support 9. A rubber gasket 15^a may be placed between the members 8 and 15 to insure a water tight joint. In the casing 15 above the valve 10 is located a partition 16 having therein a valve seat 17 in which the valve 10 seats itself when forced by pressure from its support 9, thus closing the opening 17.

Threaded to the free end of the casing 15 is the lower neck 18 of a glass guard 19 carrying therein the gauge glass 20, the lower end of which rests on the upper side 25 of the partition 16 around the valve seat 17. The upper end of the gauge glass 20 extends through the upper neck 21 of the gauge glass guard 19 and protrudes a short distance into a sleeve 22 which is threaded to the upper neck 21 of the gauge glass guard. Packing glands 23 may be provided to prevent leakage at the joints or between the gauge glass 20 and the guard 19.

To the free end of the sleeve 22 is threaded a nut 24 carrying a flanged coupling 25 which in turn carries a metal pipe 26. The free end of this pipe 26 is also fitted with a flanged coupling 25^a carried by a nut 24^a which is threaded to a lateral tubular extension 27 of a valve cage 28. The valve cage 28 is connected to and has communication with the upper valve casing 5 of the boiler 7 by means of a tubular flanged coupling 29 threaded into a tubular extension 30 in the lower portion of the valve cage and connected to a tubular extension 31 of the upper boiler valve housing 5 by means of a threaded nut 32 carrying the flanged end 33 of the tubular coupling 29.

Into the upper end of the valve cage 28 is screwed a standard pipe plug 34, and into

the lower end of said valve there is screwed a plug 35, this last mentioned plug carrying a stem 36 on which a valve 37 is adapted to be supported when at rest. This valve 37 is of identically the same structure as the valve 10 and therefore need not be described. The valve 37, when forced from its position on the stem 36, is guided by its wings acting on the walls of the valve cage 28 and seats its forward surface 13 in a valve seat or aperture 38, thus closing communication through the tubular extension 27, and pipe 26 to gauge glass 20. It will be noted that when the valve 37 is supported on the stem 36 it is located above the aperture 39 in the lower portion of the valve cage 28, which communicates through the tubular coupling 29 to the upper boiler valve 8. Thus steam may normally pass up and around the valve 37, but when extraordinary pressure is exerted, as by breaking of the gauge glass, the valve will be forced into the seat 38.

Having described my invention, the operation is as follows: The upper and lower boiler valves are open at all times, steam passing out through the upper boiler valve under the wing valve 37 and into the gauge glass 20, while water passes out from the lower boiler valve under the wing valve 10 and into the gauge glass 20. It will be understood that the equalized pressure of the water and steam in the gauge glass 20 will cause the wing valves 37 and 10 to remain at rest on their respective supports 36 and 9 by reason of their own weight, and that since the guide wings 11 terminate below the bottom surface of the valves, passage of the fluid upwardly under the valves 40 may be effected. The liquid level of the boiler will now be indicated in the gauge glass 20. When the gauge glass is fractured the equalized pressure being instantly destroyed, the wing valves 37 and 10 will be forced into the seats 38 and 17 respectively, thus shutting off the flow of the fluids and preventing the escape of the pressure in the boiler 7 and consequently scalding of persons in the vicinity. The leak ports 14 in the wing valves 37 and 10 allow for the passage of a small flow of fluid therethrough, so that after the new gauge glass 20 has been applied the same may gradually be filled with the steam and water. When the pressure within the tube again equals the pressure of the two fluids in the boiler, the valves 37 and 10 are automatically un-

seated from their seats in the apertures 38 and 17 and slide back by gravity to their normal position on the supports 36 and 9.

It will be noted that by my construction the valves 37 and 10 operate vertically in their chambers so that when the pressure in the gauge glass 20 equals the boiler pressure the valves may fall back upon their supports 36 and 9 by gravity, thus avoiding the use of springs.

While I have described the preferred embodiment of my invention, it will be understood that various changes and modifications may be made in the same within the spirit and scope of the depended claims. The invention is capable of application to all boilers having their own standard equipment, and may be readily attached thereto.

I claim:

1. The combination with the glass of a water gauge and the connecting means of said glass with the steam and water spaces of the boiler; of a valve chamber in each of said connecting means in communication at one end with the boiler and having at the other end a valve seat communicating with the glass, a valve support in the first-mentioned end of said chamber, a valve in said chamber normally resting in spaced relation to said support, and wings extending laterally from the valve and longitudinally below the lower end thereof for engagement with said support, said wings operating on the wall of the valve chamber to guide the valve into the valve seat when it is actuated.

2. A valve comprising a cylindrical body portion having a conical head at one end, and radially directed guide means attached to said body portion and extended beyond the other end.

3. The combination with the glass of a water gauge and the connecting means of said glass with the steam and water spaces of the boiler; of a valve chamber in each of said connecting means in communication at one end with the boiler and having at the other end a valve seat communicating with the glass, a valve in said chamber, wings extending laterally from the valve and longitudinally below the lower end thereof, for spacing the valve from the boiler inlet, said wings operating on the wall of the valve chamber to guide the valve into the valve seat when it is actuated.

In testimony whereof I affix my signature.
JOHN PETER WULFF.
